UNITED STATES PATENT OFFICE.

LOUIS SIMONICH, OF L'ANSE, MICHIGAN

COLLAPSIBLE STEPLADDER.

Application filed December 19, 1922. Serial No. 607,806.

To all whom it may concern:

Be it known that I, LOUIS SIMONICH, a citizen of the United States of America, residing at L'Anse, in the county of Baraga and State of Michigan, have invented certain new and useful Improvements in Collapsible Stepladders, of which the following is a specification.

This invention relates to certain new and useful improvements in collapsible step ladders wherein the device rigidly set up in step ladder formation may be collapsed and moved upon hinge connections between sections thereof to provide a support for a table top, or be suspended in the form of a bench or swing.

A further object of the invention is to provide in connection with a collapsible step ladder wherein connected side rails are pivoted together at their upper ends, a novel type of brace for holding the side bars in spaced relation and rigidly disposed relative to each other.

With the above general objects in view
25 and others that will appear as the nature of
the invention is better understood, the same
consists of the novel form, combination and
arrangement of parts hereinafter more fully
described, shown in the accompanying draw-
30 ing and claimed.

In the drawing, wherein like reference characters designate corresponding parts throughout the several views,

Figure 1 is a side elevational view of a collapsible step ladder in its set-up position, and constructed in accordance with the present invention,

Figure 2 is a front elevational view of the device,

40 Figure 3 is a rear elevational view,

Figure 4 is a horizontal sectional view taken on line IV—IV of Fig. 1 showing the tensioned spacer detachably connected to the hinge members carried by adjacent ends 45 of the side bar sections of the latter.

Figure 5 is a top plan view of the tensioned spacer indicating by arrow lines the direction in which the legs of the spacer are moved for placing the same under tension,

50 Figure 6 is a top plan view of the ladder collapsed and horizontally disposed for supporting a table top,

Figure 7 is a side elevational view of the ladder in partly collapsed form and suspended as a swing from a housing structure,

Figure 8 is a fragmentary perspective

view showing the connection between one arm of the tensioned spacer and the hinge sections carried by adjacent ends of side bars, and

Figure 9 is a detail sectional view taken on line IX—IX of Fig. 7 showing the pivotal strap connection between adjacent ends of the hinged sections.

Referring more in detail to the accompanying drawings, and particularly to Figs. 1 to 5, and 8, wherein the device is illustrated as set up in its step ladder formation, the device embodies a front frame including spaced upper side bars 1 and spaced lower side bars 2 pivotally connected at their meeting ends in a manner to be hereinafter described. The side bars 1 and 2 are connected by steps 3.

The rear frame of the ladder construction embodies spaced upper side bars 4 and spaced lower side bars 5 pivotally connected at their adjacent ends while spacing rods 6 extend between the side bars 4 and 5 at the upper and lower ends thereof. 75 80

The upper ends of the side bars 1 and 4 are hingedly connected as at 7 while the outer upper edge of each of said bars 1 and 4 carries a strap bearing 8 that has alined therewith strap bearings 9 depending from the top plate or rest 10 and through which bearings 8 and 9 a rod 11 extends for removably securing the top plate in position on the upper ends of the side bars 1 and 4. 85

The hinge connection between the side bars 1-2, and 4-5, is more clearly shown in Figs. 4, 5 and 8, the inner face of the lower end of the upper side bar carrying a hinge plate 12 carrying a barrel 13 that is aligned with a barrel 14 carried by a hinge plate 15 fixed to the inner face of the upper end of each lower side bar. A tensioned spacer formed of a pair of resilient bar or wire members has said members twisted together intermediate their ends as at 16 and bent at angles to the twisted portion to provide extension legs 17 having bent ends 18, the tensioned spacer normally assuming the position as shown in Fig. 5 when disengaged from the latter construction. The legs 17 and bent ends 18 of the spacer member are moved toward each other at opposite ends thereof against the resiliency to position the bent ends 18 for reception in the aligned barrels 13 and 14 of the hinge plates 12 and 15 as shown in Figs. 4 and 8, resiliency of the spacer member maintaining the bent ends

18 operatively positioned in the aligned barrels 13 and 14 with the upper and lower side bars of the ladder rigidly spaced. To prevent pivotal movement of the upper side bars relative to the lower side bars, latch plates 19 pivotally connected as at 20 to the lower ends of the upper side bars 1 and 4 have side notches 21 adjacent the lower ends thereof to receive the pins 22 carried by the upper ends of the lower side bars 2 and 5.

When the device is to be used as a support for a table top, the top plate or rest 10 is removed from the upper side bars 1 and 4 by disengaging the rods 11 from the bearings 8 and 9, the tensioned spacer being removed from the hinge plates 12 and 15 and relatively short pins 18 substituted therefor in the barrels 13 and 14, the several side bars being shifted to provide a rectangular configuration as illustrated in Fig. 6 upon which a table top may be conveniently supported.

In converting the device into a bench or swing formation, the top plate 10 and the tensioned spacer are removed from the ladder construction, the hinge pins 18^a being substituted in the barrels 13 and 14 while bracing plates 23 of the type best illustrated in Fig. 9 are employed for connecting the adjacent hinged ends of the side bars and preventing relative movement thereof. Each plate or strap 23 is anchored to the outer faces of the adjacent ends of the side

bars by screws 24, the outer ends of the lower side bars 2 and 5 being suspended by chains 25 depending from a rafter 26 a part of a housing structure 27.

From the above detail description of the device, it is believed that the construction and operation thereof will at once be apparent, as well as the many uses for which the device may be employed, and while there is herein shown and described the preferred embodiment of the present invention, it is nevertheless to be understood that minor changes may be made therein without departing from the spirit and scope thereof as claimed.

What is claimed as new is:—

In a collapsible step ladder, front and rear frame structures embodying side bars hingedly connected at their upper ends, a top plate removably secured to the upper ends of the side bars, a tensioned spacer removably positioned between the front and rear frames, the side bars, each being formed of upper and lower sections hinged at adjacent ends, cooperating means carried by the sections for maintaining alinement thereof, the hinge connection between the sections including a hinge plate carried by the adjacent ends of each section, and a barrel carried by each hinge plate adapted to receive an end of the tensioned spacer.

In testimony whereof I affix my signature.
LOUIS SIMONICH.
